UNITED STATES PATENT OFFICE.

JUDSON MCFELL, OF CHICAGO, ILLINOIS.

FIRE-ALARM AND WATCH-SERVICE SIGNALING MEANS.

1,076,304.

Specification of Letters Patent. Patented Oct. 21, 1913.

Application filed May 8, 1911. Serial No. 625,709.

To all whom it may concern:

Be it known that I, JUDSON MCFELL, a citizen of the United States, residing at Chicago, in the county of Cook and State 5 of Illinois, have invented certain new and useful Improvements in Fire-Alarms and Watch-Service Signaling Means, of which the following is a specification.

My invention relates to improvements in 10 fire alarms and watch service signaling means, and has for one of its objects to improve generally and in detail transmission means in a system of the character described.

A further object of my invention more 15 specifically is to provide, for association with a system involving different possible signaling connections, a box providing automatic means for switching the signaling connections within the transmission box to 20 accommodate changes in the exterior signaling connections.

Another object is to provide improved non-interfering transmitters.

Other and further objects of my invention 25 will become apparent to those skilled in the art from the following description taken in conjunction with the accompanying drawings, wherein—

Figure 1 is a face view of a transmission 30 box with its cover removed, showing the parts at normal position; Fig. 2 is a similar view showing the parts in positions assumed during certain operations of the box; Fig. 3 is a face elevation of certain motor parts of 35 the box and associated devices; Fig. 4 is a transverse section on line 4—4 of Fig. 1; Fig. 5 is an isometric detail, showing the main switching mechanism of a transmitter; Fig. 6 is a sectional detail on line 6—6 of 40 Fig. 1; Fig. 7 is a detail of a switch-restoring mechanism; Fig. 8 is a general diagram showing the connection of the boxes in the system, and the interior wiring of one box; and Fig. 9 is a simplified skeleton diagram 45 of one box in one condition assumed while it is being connected in "emergency" circuit. Fig. 10 shows the same parts with the emergency connection completed.

Referring now to the construction of the 50 transmitter, 10 indicates in general the transmitter in which is provided spring motor mechanism 11 of any suitable con-

struction mounted between front and back plates 12 and 13 and providing a spring winding arbor 14 and a number wheel arbor, 55 15. The motor mechanism is of any convenient construction and is so well known as to need no particular description.

The number wheel arbor 15 carries the usual signaling or number wheel 16 having 60 peripheral teeth, 17, corresponding numerically and in grouping with the number to be transmitted by the box, and the winding arbor 14, extending through the face plate 10' of the box, carries exteriorly a winding 65 handle 18, used only for fire alarm purposes to wind the arbor to its fullest intended extent.

The winding arbor bears a lever arm 20, having a downwardly bent terminal nose 70 21 for purposes to be described, said lever 20 having lost-motion connection by a screw 22 and slot 23 with a vertical switch-setting link 24, slotted as at 25, for engagement with a guide screw 26, on the guide stud 27 for 75 vertical sliding movement, and at its lower end provided with a bearing roller 28. The box cover 10' carries a short shaft 30, projecting through the front thereof to receive a watchman's key, said shaft having mounted thereon inside the box a lever arm 31, one end of which co-operates with the roller 28, so that when the watchman by means of the key turns the shaft 30, to such extent that the lever 31 partly rotates until its heel 80 strikes, and is stopped by, the bottom wall of the casing, the link 24 is forced upward a predetermined distance, to potentiate or set the motor mechanism for a short operation 85 to transmit a watchman's signal. The motor thus partly wound may be capable of rotating the wheel 16 say twice before running down, while when fully wound, it may be rotated say six times.

The link member 24 carries a laterally 90 projecting nose 24', arranged to co-operate with a movable switch element of a main switch 32, to make changes in the switch connection differing according to whether the link 24 receives a short movement 95 due to setting of the watchman's call, or its long movement due to the setting of a fire alarm signal. The movable switch element 33, in the specific construction 100

which I preferably employ, is a metallic slide having slots 34 engaging guide screws 35 which project from an insulating base 36, the slide member 33 being acted upon by a 5 spring 37 interposed between a fixed pin 38 on the plate and the pin 38' on the slide, normally to hold the slide in lowest or retracted position. The slide carries a lateral leaf 39, bearing on its upper and lower surfaces 10 faces contact plates insulated from leaf 39 and forming a movable switch blade 40. The stationary contacts are arranged, preferably, so that three different connections may be effected accordingly as the movable 15 blade 40 stands in normal position. To this end, I provide upon the insulated base four contacts, each of which has two spring leaves for knife switch action. These stationary contacts 41, 42, 43, and 44 are arranged 20 in opposing lower and upper pairs respectively, each pair comprising one short leaf and one long leaf, the long leaf of each pair confronting the short leaf of the opposite pair, and the long leaves of the 25 two pairs laterally overlapping but laterally separated. Thus, when the blade 40 is in lowest position it connects switch members 41 and 42; when in the intermediate position to which the switch blade 40 is raised by 30 the operation of the watchman's lever 31, contacts 41 and 44 are interconnected; and when the movable contact is raised to its highest position, by operation of the winding handle 18, contacts 43 and 44 are connected 35 thereby.

The main switch slide 33, heretofore referred to, has an offset portion 46 with which the nose 24' of the switch-moving link 24 coöperates, the upper extremity of said 40 offset portion 46 being beveled as at 46', and in the offset portion I provide latching openings, 47 and 48, arranged to be engaged by a latching member to hold the movable switch member in either of its raised positions. 45 The latch member shown comprises a lever 50, pivoted on stud 25, provided with a beveled latch pin 51, for engagement in either aperture 47 or 48, the extremity of said lever having a roller 52 to be acted upon by the 50 nose 21 of lever 20 to throw the latch member to ineffective position when the lever 20 is down in its normal position, the latch member being acted upon also by a spring 53 tending to force it into latching position. 55 Thus, as soon as the motor is partly or fully wound, and the lever 20 accordingly moved away from the roller 52 of the latch member, said latch member is impelled by spring 53 into operative position, and when the switch 60 slide 33 is partially elevated, by the setting of the watchman's signal, the latch point 51 engages notch 47 to hold the switch blade 40 cross-connecting contacts 41 and 44 until the latch is positively released; while further

upward movement of the slide 33 due to the 65 setting of a fire alarm signal causes the latch point 51 to engage in notch 48, holding the switch slide in such position that its contact 40 cross-connects stationary contacts 43 and 44, until the release occurs. The unlatching 70 or release action occurs when the motor has practically run down, the very last portion of the movement of lever arm 20 throwing over the latch lever 50, to withdraw the point 51 from latching engagement with the 75 switch slide 33, thereby to free the slide for retraction to normal position under the influence of its spring, 37. Thus, it will be apparent that regardless of the remaining mechanism to be described, the apparatus 80 thus far specified provides means whereby a short operation of a movable part, *i. e.*, the link 24, conditions or prepares the transmitting mechanism for a short watch-signaling operation, occasions the movement of the 85 switching mechanism to effect one set of switching connections, and permits the latching of the movable switch blade in such position; while a more prolonged movement 90 of the said movable part fully winds or potentiates the motor, effects a different set of switching connections, and causes the switching mechanism to be latched in its appropriate position, the latching operation 95 maintaining the switch in set position in either event until the motor is substantially run down.

The teeth 17 of the signal wheel 16 are made to actuate a signaling switch or circuit breaker 55, comprising the usual spring pens 100 or contacts, and these are connected in circuit with a controlling electromagnet 56, having its armature 57 so equipped and arranged that only when the armature stands in attracted position each time the pens 55 105 are closed by a tooth 17, is the signal wheel allowed to rotate. To this end, the armature 57 has a lever extension 58, having pivoted to its extremity a pawl 59, the nose of said pawl being shaped for latching operation 110 with pins 60, one for each tooth 17, carried by the wheel 16. The tail 62 of the pawl has a limited range of movement but as far as the function of the stopping of the signal wheel is concerned, this may be disregarded 115 and the pawl considered merely as a hook-like nose upon the armature lever 58, for stopping the rotation of the wheel 16. The relative disposition of the teeth 17, pins 60, and pawl 59, is such that whenever armature 120 57 is attracted, the pawl 59 is thrown out of the path of the pins 60; but when the armature is retracted, the pawl is interposed in the path of the pins 60, each pin 60 coming into engagement with such pawl during 125 the time that the corresponding tooth 17 has effected a closure of the signaling pens 55.

It is desirable that the pawl 59 should

functionally operate only under certain conditions incident to fire alarm signaling, and therefore that the armature 57 should be mechanically retracted from its magnet 56 only when the box is set for the transmission of a fire-alarm signal. To these ends, I provide for the armature 57 a spring 65 connected to one end of the armature and at the other end to a pin 66 upon the slide member 33 of the main switch mechanism 32, so that when the switch slide 33 is in either of its two lower positions,—that is, normal position, or watchman's signaling position,—the spring 65 works as a light pressure spring tending to throw the armature positively into contact with its magnet poles, but when the slide 33 is raised to highest or fire alarm position, spring 65 is put under a retractile tension, as indicated in Fig. 2, mechanically to throw armature 57 to retracted position (conditioning the pawl 59 for operation), except when the spring 65 is overcome by the attraction of magnet 56 for its armature.

The purpose of making the pawl 59 movable is to enable it to be used to actuate an emergency switch whenever pawl 59 is engaged and moved by a pin 60 on the signal wheel. To this end, the emergency switch 67 is mounted upon the armature lever 58 in insulated fashion, the leaves of the switch being normally open, and arranged to be closed whenever the insulated tail 62 of the pawl 59 is forced toward the armature lever by the action of a pin 60, pressing against the nose of the pawl 59.

The purpose of the emergency switch 67 is to control the circuit for an emergency magnet 70, the armature 71 of which governs the operation of a switch set 72, which I will for distinction term the emergency circuit changer. This emergency circuit changer 72, in the form shown, comprises a main leaf 73 held raised under tension by the insulated extremity of armature 71, so that it contacts with the upper switch point 74. When the armature 71 is attracted by its magnet 70, and releases the strong switch spring 73, the latter springs into contact with a lower switch point 75, and also acts through a suitable insulated block upon the bottom contact spring 76 to force the latter out of contact with the spring 75. The switch set 72 thus normally stands with its middle spring contacts 73—75 separated, and its functional operation is to make contacts between the middle spring leaves 73—75, freeing them both from connection with the extreme leaves. After the armature 71 once loses its latching engagement with the main leaf 73, said leaf remains in functionally operative lowest position until it is again raised by a restoring lever of bell crank shape, indicated at 77, having one insulated arm underlying the long spring 73, and its other arm interposed in

the path of movement of a tail 78 of lever 20, so that just as the lever 20 reaches its final position of rest after an operation of the box, it throws over the bell crank 77, causing its horizontal arm to lift the spring 73, so that the armature 71 may drop into latching position beneath it.

The interior wiring of the box terminates at three external binding posts 81, 82, and 83, for external circuit connections, the first said binding post 81 having wiring connections 84 to one pen of a make-and-break signaling switch 55, the remaining pen of said switch 55 having connections 85, to one terminal of magnet 56, and connection 86 to one leaf of the emergency switch 67. The two remaining external binding posts 82 and 83 have direct connections 87 and 88 respectively to the main switch contacts 41 and 42, so that normally connection is made therebetween by the switch member 40. The main switch contact 41 has a wire connection 90 to the main leaf 73 of the emergency circuit changer, and the outer leaf 74 normally contacting therewith has wire connection 91 to one terminal of the emergency magnet 70, the other terminal of which is connected by wire 92 with the remaining limb of emergency switch 67. The free terminal of magnet 56 has a connection 93 with the upper main switch contact 44, companion contact 43 having wiring connection 95 to the third leaf 75 of the emergency circuit changer 72, the leaf 76 normally contacting therewith being wired as at 96 to the main switch contacts 42, to complete the interior wiring of the box.

While the transmitting box having some or all of the features above described may be connected and operated in various circuits, I have for illustration herein shown the box as connected in a circuit similar in general arrangement to that described in my prior Patents No. 797,907 and No. 828,420.

Specifically, 100 indicates a central battery from which extends the "positive battery end" 101, of a line wire including a relay magnet 102 and looped as at 101, continuously to the binding posts 81 of the various boxes of the circuit (from right to left in the drawing, Fig. 8) returning to the central station by a "positive tell-tale end wire" 103, terminating at the switch blade 104 of a double throw "emergency" line switch, the upper contact of which is normally engaged by the switch lever 104 and wired as at 105 to a high resistance tell-tale magnet 106. The remaining or lower terminal of the switch 104 has connection 107 with the "positive battery end" 101 beyond the relay 102, so that when the switch 104 is thrown down, it completes a double-loop of the wires 101 and 103 for emergency signaling purposes. A normally open push

button switch is bridged across from switch arm 104 to the lower contact for certain test purposes to be described.

- From the opposite terminal of the battery 5 runs a wire 110 which I will distinctively term the "negative battery end" of the line wire, including a fire alarm register 111 and bell 111' and the magnet of a line relay 112, said negative battery wire leading to the binding 10 post 83 of the left hand transmission box 10' of Fig. 8 which is last with respect to the wire 101, the middle binding post 82 of said box having connection 110' to the binding post 83, and so on to the box first 15 in the positive line wire 101, whence binding post 82 has connection through negative tell-tale wire 113 with the double-throw switch 114, normally engaging an upper contact, but having its lower "emergency" 20 contact connected by wire 117, including an emergency relay 111^a and bell 111^a' with the wire 110, and provided with the test button 118, to bridge the lower switch opening, in simulation of the connection 107-108 of the 25 opposite tell-tale wire heretofore described. The upper terminal of the switch 114 is preferably connected by wire 119 including a non-inductive resistance 120 with a watchman's time recorder 121, having its remaining 30 terminal connected by wire 122 through a switch 123 (controlled by line relay 102) and wire 124 with the tell-tale magnet 106. Thus, it will be observed that normally the 35 circuit is closed as long as each box stands with its main switch blade 40 engaging the two contacts 41, 42, the circuit path being 100, 101, 102, loops 101', 103, 104, 105, 106, 123, 122, 121, 120, 119, 114, 113, box connections 82, 87, 41, 40, 42, 88, 83, right hand 40 loop 110' (and so on through the series of boxes), negative battery end 110, 112, 111', 111, 110. The high resistance magnet 106 reduces the current to such an extent that 45 neither the registers or gong 111 and 111', nor the relays 102, are operatively energized, these instrumentalities standing dormant as in an open circuit system, but the high resistance tell-tale magnet 106 being sufficiently energized to hold its armature 106'. 50 Each of the line relays 102 and 112, when energized by the battery 100 through a circuit of low resistance will attract its armature, releasing a switch stem 102' or 112', as the case may be, for functional operation. 55 For simplicity, these switch stems are shown as gravity operating, for manual reset.
- The switch stem 102', when released for functional movement by the relay 102, closes a switch 126 in a shunt connection 127, 60 around the relay coil 102, so as to cut the resistance of the relay coil out of circuit as soon as the relay coil has performed its function. The similar switch stem 112' is similarly arranged to close a switch 128 in a shunt 65 129, for the relay coil 112. The ar-

mature 106' of tell-tale magnet 106 controls the switching element 130 for functional operation when the tell-tale magnet is deenergized. The switch stem 130 when operated closes a switch 131, controlling a local circuit for a tell-tale bell 132, said circuit extending from the positive battery terminal by wire 133 through a switch 134', normally closed by the switch stem 102' of relay 102, and arranged to be opened by a 70 functional operation of said switch stem, said circuit continuing by wire 134 to the normally opened switch 131 of the tell-tale relay 106, and thence by wire 135, including the tell-tale bell 132, back to the negative 80 terminal of the battery. The switch stem 130 also controls a switch 136, normally opened, governing a circuit connection for directly connecting a terminal of the watch register, 121, with the negative terminal of 85 the battery. Specifically, 137 indicates a wire connected from wire 122 to normally opened switch 136, the remaining terminal whereof is connected by wire 138 with a normally closed switch 139 governed by the 90 switch stem 112' of the line relay 112, the circuit from such switch continuing by wire 140 to the negative terminal of the battery.

The operation of the system will be as follows; it being remembered that the normal 95 circuit is as shown in heavy lines in Fig. 8 and as heretofore specifically traced.

Watch service alarm.—Assuming that the watchman operates the middle box 10^b of the three shown in Fig. 8, by turning stem 100 30, (Fig. 1) with his key, link 24 is partially lifted to wind the winding arbor 14, enough to cause two revolutions of signal wheel 16, and also to cause nose 24' of the link to move the switching slide 30 so as to 105 move blade 40 of main switch 32 to its middle position to effect connection between contacts 41 and 44, the main switch being latched in its new position by latch lever 50. By this operation of the main switch, 110 the main line circuit is broken within the box between the terminals 82 and 83 but the watch-service circuit is prepared for closure by the operation of the signaling pens 55. The rupture of the normal circuit, thus 115 effected deenergizes high resistance tell-tale relay 106, so that its switch stem 130 drops to close switches 131 and 136. Closure of the switch 131 starts in operation the tell-tale bell 132, through the circuit 100, 133, 120 134', 134, 131, 132, 135, 100. This condition continues momentarily only, for as soon as the first tooth of the signal wheel 17 of the active box closes the switch pen 55 of the transmitter, a low resistance watch-service 125 circuit is established as follows: 100, 101 (102), loop 101' to the active box 10^b, through the box from terminal 81, by path 84, 55, 85, 56, 93, 44, 40, 41, 87, to terminal 82, and thence back through the tell-tale 130

end of the negative line wire by loops 110', normal box connections 83, 88, 42, 40, 41, 87, 82, of the intervening box 10', return wire 113, switch 114, connections 119, 120, 5 watchman's recorder 121, and the negative battery connections 137, 136, 138, 139, 140, 100, such connections having been just previously closed by the dropping of the switch stem 130 for the tell-tale high resistance magnet 106. The watch-signal circuit thus established, eliminating the high-resistance magnet 106 is of such low resistance that the relay 102, included in the circuit, becomes operatively energized and releases its 10 switch stem 102', so that the latter drops and closes switch 126, thereby to cut the resistance of coil 102 out of the line, and at the same time opens both switches 123 and 134', thereby to stop the operation of the tell-tale bell 132 and positively to disconnect the tell-tale magnet 106 from any energized circuit. Of course, such make-and-break action of 15 pens 55 is recorded by register 21.

It will be observed that a watchman's signal is transmitted over a circuit established 25 through the out-going "battery end" of the positive line wire and the incoming "tell-tale end" of the negative wire, the latter having been automatically connected to the negative terminal of the battery in such 30 manner that it includes the watch service recorder, 121, and excludes the fire alarm service recorder 111.

In considering the operation of the transmitter 10^b, in sending a watch service call, 35 no attention need be paid to the action of pawl 59, for it will be remembered that the movement of slide 33 effected by the partial winding of the box for watch service signaling is not sufficient to put spring 65 40 under retractile tension, so that the armature 57 makes no vibrations and the pawl 59 accordingly performs no function. It will be remembered, however, that when the 45 watchman's signal is completed, the return of the box lever 20 to normal position trips the latch 50 that holds the slide 33, enabling the slide to be retracted to normal position, thereby restoring the box circuit connections to normal, throwing the switch member 40 into position again connecting contacts 41 and 42. The various switch-stems 50 at the receiving station will be manually restored.

55 *Fire alarm signal.*—When the transmitter is set, by means of the winding handle 18, to send a fire alarm signal, link 24 is raised through its full excursion, throwing slide 33 upward until the main switch blade 40 60 makes connection between contacts 43 and 44, and is latched in uppermost position by latch member 50. This movement of slide 33 puts the spring 65 under tension, so that it forcibly retracts the armature 57, throwing 65 the pawl 59 into the path of pins 60

upon the signaling wheel 16. This operation opens the normal circuit between terminals 82 and 83 of the active box and causes the deenergization of the tell-tale magnet 106 with the consequent closing of 70 the switches 136 and 131 as heretofore described, and it prepares what I will hereafter term the "main" signaling circuit for the transmission of the fire alarm signal. As soon as the first tooth of the number wheel 116 closes signal switch pens 55, however, a low resistance fire alarm signaling circuit is established as follows: 100, 101, loops 101', terminal 81 of the active box; internal connections 84, 55, 85, 56, 93, 44, 43, 95, normally closed contacts 75 and 76 of the emergency circuit changer, wires 96 and 88, to box terminal 83; thence by left-hand loop 110', and the normal connections 82, 87, 41, 40, 42, 88, 83, of the left hand box 10^c, and negative battery end 110 through the relay 112, gong 111', fire alarm register 111, to battery 100. Obviously, the opening and closing of switch 55 by the signal wheels causes the fire-alarm register to record the fire alarm signal as the box runs down, occasioning say six full revolutions of the signal wheel 16. Under these conditions, both line relays 102 and 112 are energized, each releasing its switch stem 95 thereby to cut the resistance of the relay coils out of circuit and to open the various subsidiary circuits controlled by the said relays 102 and 112, that is to say, the circuits for tell-tale bell 132 (at switch 134): 100 the circuit for high resistance magnet 106 (at switch 123); and the circuit for the watchman's alarm register 121 (at switch 139).

It will be noted that in this regular operation of the transmitter to send a fire alarm, the pawl 59 in the transmitting box plays no active part, for as each pin 60 approaches the pawl 59, the main signaling circuit is closed by the action of a tooth 17 upon the pens 55, thereby energizing the magnet 56 to attract its armature and throw the pawl 59, carried by the armature lever, out of the path of the approaching pin 60, so that in the regular operation of the fire alarm transmission, the pawl 59 dodges around each pin 60, and permits the unimpeded transmission of the signal.

It will be observed that in the regular fire alarm transmission, the main signal circuit 120 is completed through the out-going positive battery end and the out-going negative battery end of the circuit, thereby including the fire alarm recorder 111 and excluding the watch service recorder 121.

As thus far described, the results of the operation of my system are substantially the same as those attained by the system described in my prior Patent No. 828,420, although the apparatus is different. 130

Emergency connections.—It will be apparent, however, that the accidental rupture of either battery end wire 101 or 110 would render impossible the establishment of the main (fire alarm service) signal circuit described, and as it is highly important that the transmission of fire alarms should not be prevented by such accidental break of the circuit, the auxiliary emergency mechanism of the box and the emergency connections for the lower contact points of switches 104 and 114 are provided to enable any box to operate notwithstanding the rupture of either or both wires of the main signaling circuit.

Assuming the circuit to be accidentally ruptured at the point *z* in the positive battery end 101, it will be obvious that the tell-tale magnet 106 will become deenergized, dropping its armature, and starting in operation the tell-tale bell 132. The bell will continue to ring, but none of the registers will make any record, so that the central station attendant is promptly acquainted with the fact that the line is broken. It may be immediately determined which line wire,—positive or negative—has been ruptured by the operation of the test buttons 108 and 118. With the line broken as described, if the test button 108 is closed and the armature 106' lifted into contact with the magnet 106, it will be retained, as the tell-tale magnet will receive positive battery connections through the path 100, 101, 107, 108, 104, 105, its negative battery connections being undisturbed. The test operation of the other button 118, however, will not cause the energization of the magnet 106 under the circumstances described because the negative tell-tale wire will simply be looped back to the negative battery end, while the magnet 106 has no closed connections with the positive terminal of the battery. Upon thus ascertaining that it is the wire 101 that is broken the attendant throws switch 104 to its lower contact, completing the emergency connection of the tell-tale end of the circuit with the positive terminal of the battery through wire 107. Under these conditions, the operation of the fire alarm signal is identical with that heretofore described, the only difference being in the connection of the positive terminal of the battery to the box terminal 81, which is made through path 101, 107, 104, 103, 101', 81.

If the negative battery wire 110 is broken as at *y*, switch 114 is operated by the attendant to loop the negative "tell-tale" wire 113 to the negative battery end 110, through the wire 117 and register 111^a. Under such circumstances, the emergency connections of the transmitter are called into play when the transmitter is actuated to send a fire alarm signal, and the circuit

for signaling is changed to what I shall term, distinctively, the "emergency" signaling circuit. Thus, upon the commencement of the fire alarm signal, the number wheel 16 runs until it closes the switch 55, but under the circumstances now considered, the closure of the switch 55 does not establish a circuit for the magnet 56, because ordinary current path 84, 85, 56, 93, 95, 96, 88, 83, leads only to the wire 110 which is broken. Consequently magnet 56 is not energized and cannot attract its armature so that the first pin 60 on the signal wheel engages the pawl 59 carried by said armature. When, however, the pin 60 strikes the pawl 59, it rocks the pawl slightly, causing its heel 62 to close the switch 67, and thus to establish a circuit for emergency magnet 70 as follows: 100, 101, (102), 101', 81, 84, 55, 86, 67, 92, 91, 74, 73, 90, 87, 82, 110', right hand box terminals 83—82, tell-tale end 13 of the negative line wire, switch 114 (thrown down), 117 (111^a, 111^{a'}) 110, 100. Such circuit connection includes the emergency magnet 70 and the latter attracts its armature, freeing the spring 73 of the emergency circuit changer 72 which flies into contact with spring 75, opening both the normal connections 74—73 and 75—76. This action of the circuit changer opens the circuit just before made for the emergency magnet 70 between points 73—74, and also opens the connection between main switch contacts 42—43 at circuit changer contacts 75—76, but establishes a connection between energized binding posts 81 and 82 including in series the switch pens 55 and the magnet 56 to complete the emergency circuit as follows: 100, 101 (102), 101', 81, 84, 55, 85, 56, 93, 44, 40, 43, 95, 75, 73, 90, 87, 82, 110', box 10^a, 105, 113, 114 (thrown down), 117 (111^a, 111^{a'}), 110, 100. Fig. 10 shows diagrammatically the salient elements of the circuit under the conditions just described. Thus, the effect of the emergency operation is to throw the box connections for the signal pens 55 and the controlling magnet 56 from the terminal 83, connection of which to the negative battery end of the circuit has been broken at *y*, to the terminal 82 connection of which to the battery through the negative "tell-tale" end of the circuit has been made through switch 114. As soon as this is done the box begins to operate in ordinary fashion, controlling magnet 56 being included in the "emergency" circuit with pens 55, so that the latch point 59 will dodge around pins 60 of the signal wheel as heretofore described.

Should the normal circuit become short circuited, as at *z*, Fig. 8, the operator at central throws switch 114 down, and manifestly the fire alarm may be transmitted

from either side of the "short" z . Thus, to the left of z movement of switch 40 in preparing the box 10^b for fire signal breaks the circuit established through the short z and the fire alarm transmission is in ordinary fashion. In box 10^b , however, movement of switch blade 40 followed by the closure of pen 55 merely throws magnet 56 into parallel with the short z ,—or in other words, magnet 56 is short circuited, so that the magnet is not effectively energized and the pawl 59 throws the emergency switch 67, initiating the emergency operations which result in the transmission of the complete fire signal through the emergency circuit. This automatic shifting of the connections of the signaling switch pens from an ordinary or main circuit to an emergency circuit whenever the emergency circuit is available and the main circuit is not, is the most important function of the emergency connections, provided by switch 67, circuit changer 72, and emergency magnet 70, and I believe it to be broadly new.

Non-interference.—The mechanism—specifically, the pins 60 and the pawl 59 for stopping the wheel—whereby the operation of the box is stopped except when the magnet 56 is thrown into an energized circuit each time the switch pens 55 are closed in the sending of a fire alarm signal performs another highly important function, however, in making the boxes non-interfering in the performance of their fire alarm functions.

Remembering that in the ordinary fire-alarm operation of the transmitters,—where no line wire is broken and the central station switches 104 and 114 stand in normal position, as illustrated in Fig. 8,—the completion of the signaling circuit from a right hand box (that is, a box near the tell-tale end of the negative battery wire) depends upon the maintenance of connections between the terminals 82 and 83 of all boxes to the left thereof (that is, nearer the central battery with respect to the negative battery wire 110), it will readily be understood that if the right hand box 10^a of Fig. 8 is first started to send a fire alarm signal and then the middle box 10^b of said Fig. 7 is thereafter actuated to send its fire alarm signal, the main signal circuit for the box 10^a is opened by the movement of the main switch blade 40 of the middle box out of contact with its switch springs 41—42.

Consequently, the right hand box is checked in its signaling operation and stands idle until the middle box has completed its signal transmission, for the reason that as soon as the middle box is started in operation and breaks the signaling circuit for the right hand box, the magnet 56 of said right hand box, deprived of current, permits its

armature to stand retracted so that the pawl 59 is engaged by the next approaching pin 60, and said pawl positively holds the signal wheel of the right hand box against further operation until the normal circuit for the said right hand box is restored after the completion of the operation of the middle box. The operation of switch 67 by the pawl 59 produces no result, for it will be remembered (see Fig. 8) that said switch connections with wire 113 of the emergency circuit, are now disconnected from battery at central station switch 114. Of course, as soon as the middle box completes its operation, the right hand box resumes its functional operation and completes the transmission of its signal, the fact that each box sends a plurality of rounds of the signal wheel in the transmission of a fire-signal, insuring that no amount of interruption reasonably possible will prevent the transmission of a readable signal from the box most remote from the central station.

While I have herein described in detail a particular embodiment of my invention for purposes of full disclosure, and utilizing my invention in the same general type of system as that disclosed in my prior patent herein referred to, it will be apparent to those skilled in the art that the specific installation herein indicated is illustrative only, and that many changes might be made in the specific construction and connections without departure from the spirit of my invention and within the scope of the appended claims. It will also be understood that on account of the number of switches, relays, terminals, etc., in the system, I often employ in the claims specific designations of parts for sake of clearness, but such designations are intended for identification only, and not for limitation.

What I claim is:

1. In a signaling system, connections to establish a main signaling circuit, connections to establish an emergency signaling circuit; and a transmitter comprising a signaling switch, connectible in the main signaling circuit, and means responsive to the establishment of the emergency circuit upon occurrence of predetermined conditions in the normal circuit, for automatically varying within the transmitter the wiring connections of said signaling switch to connect it in operative relations to the emergency circuit.

2. In a signaling system, the combination with a central battery and a register, connections to establish a main signaling circuit, connections closable at central station to establish an emergency circuit in the event of rupture of said main circuit, and a transmitter comprising a signaling switch, manually operable means to connect said

switch in the main signaling circuit, and means automatically operable to connect said switch in the emergency circuit when the main circuit is broken and the emergency circuit otherwise closed.

3. In a signaling system, connections to establish a main signaling circuit; connections to establish an emergency signaling circuit; and a transmitter comprising a signaling switch normally connectible for operation in the main signaling circuit, an electro-responsive device for inclusion in the emergency circuit, and means governed by the action of said electro-responsive device in the emergency circuit for automatically connecting said signaling switch to operate in the emergency circuit upon the occurrence of predetermined conditions in the normal circuit.
4. In a signaling system, the combination with a source of current supply, of a battery line wire having a return end connectible to the battery line wire to form a metallic loop; an opposite line wire from the source of supply; and a transmitter comprising a signaling switch, means to establish connection therefor between the last said line wire and the first said battery line wire for completion of a main signaling circuit, and means made effective by certain conditions in the said main signaling circuit for varying within the transmitter, the wiring connections of said switch to connect it with the return end of the first said wire, for completion of an emergency metallic signaling circuit.

5. The combination of a signal transmitter, comprising a signaling switch, motor driven operating means therefor and an electro-responsive device, connected with said switch; connections to establish a main signaling circuit including said switch and responsive device; connections including a normally open emergency circuit changer, operable to establish an emergency metallic circuit for the signaling switch; and automatic means within the transmitter controlled by the electro-responsive device for closing said emergency-circuit-changer connection to establish the emergency circuit upon rupture of the main signaling circuit for said electro-responsive device and signaling switch.

6. In a signaling system, a source of current, connections to establish a main signaling circuit for a transmitter, connections for establishing an alternative emergency circuit for said transmitter, and the transmitter comprising a signaling switch, a controlling electro-responsive device and a main switch operable when the transmitter is prepared for signaling operations, to connect said signaling switch and electro-responsive device in the main circuit to the exclusion of the emergency circuit connec-

tions, an emergency magnet, means controlled by the controlling electro-responsive device for connecting said magnet in the emergency circuit connections upon rupture of the main signaling circuit, whereby said emergency magnet is energized if the emergency circuit be otherwise closed, and means controlled by said emergency magnet, for connecting the signaling switch in said emergency circuit.

7. In a signaling system, a source of current, connections to establish a main signaling circuit for a transmitter, connections for establishing an alternative emergency circuit for said transmitter in the event of rupture of the main circuit, and a transmitter comprising a signaling switch, a controlling electro-responsive device and a main switch operable when the transmitter is prepared for signaling operations, to connect said signaling switch and the electro-responsive device in the main signaling circuit to the exclusion of the emergency circuit, an emergency magnet, means controlled by the controlling electro-responsive device for connecting said emergency magnet in the emergency circuit connections when closure of the signaling switch fails to energize the controlling device, whereby said emergency magnet is energized if the emergency circuit is otherwise closed, and means controlled by said emergency magnet for connecting the signaling switch in said emergency circuit and cutting out the emergency magnet.

8. In a signaling system, a source of current, connections to establish a main signaling circuit for a transmitter, connections for establishing an alternative emergency circuit for said transmitter, and the transmitter comprising a signaling switch, a controlling electro-responsive device and a main switch operable when the transmitter is prepared for signaling operations to connect said signaling switch and electro-responsive device in the main signaling circuit, and emergency magnet, means controlled by the electro-responsive device for connecting said emergency magnet in the emergency circuit when closure of the signaling switch fails to operate the main signaling circuit, whereby said emergency magnet is energized if the emergency circuit is otherwise closed, and means controlled by the emergency magnet for connecting said signaling switch and controlling electro-responsive device in the emergency circuit.

9. In a signaling system, a transmitter providing terminals, 81—82—83, a single signaling switch, and a controlling magnet, a main switch operable to effect connection of the signaling switch and controlling magnet between terminals 81—83, and means controlled by the controlling magnet for automatically changing the connections of the said signaling switch to terminals 130

81-82; in combination with a source of current supply for establishing a signaling circuit connection through box terminals 81-83, and an emergency circuit through 5 box terminals 81-82.

10. In an alarm system, a source of current supply, a main circuit comprising two line wires having their battery ends constantly connected to the source of supply, 10 and their tell-tale ends normally connected to a high resistance device, means for establishing emergency connection of the tell-tale end of one of said wires to its battery end, and a signal transmitter comprising 15 a signal switch, means to connect said signaling switch for signaling through the battery ends of the wire, and means rendered effective by continued rupture of one of said battery wires, automatically to connect the 20 signaling switch with the tell-tale end of said wire.

11. In an alarm system, a source of current supply, a closed circuit comprising two line wires having their battery ends constantly connected to the source of supply, a 25 high resistance device normally connected to the opposite tell-tale ends of the said line wires, signal-means rendered effective by said high resistance device in response to a break in the closed circuit; means for establishing emergency connections between such tell-tale ends of the line wires and the respective battery ends, a signal receiving device connected in the closed circuits, and 30 emergency circuits; and a signaling transmitter arranged to transmit a signal through the battery ends of the line wires and provided with means for automatically accommodating the internal connections of the 35 transmitter to signal through the emergency tell-tale end connection of one of said wires when its battery end is broken.

12. In an alarm system, a source of current supply, a closed circuit including outgoing battery ends and incoming tell-tale ends closed through a high resistance tell-tale magnet at central station, independent means for connecting the tell-tale end of each wire to its battery end, means for 45 testing the continuity of each wire independently, and signaling devices associated with the circuit.

13. In an alarm system, transmitters, a source of current supply, a normally closed main circuit comprising two wires extending 50 from the source of supply, each through a battery end into connection with all of the transmitters and back to central station through a tell-tale end, a tell-tale magnet 55 wherethrough the tell-tale ends of said wires connect, a normally open connection between the tell-tale end of each said wire, and its respective battery end, testing switches for closing either of said connections without cutting out the tell-tale mag-

net, and other means for closing either of such connection and cutting out the tell-tale magnet.

14. In a signaling system, main signaling circuit connections; emergency circuit connections; and a transmitter comprising a motor, a number wheel driven thereby, a signal switch for said number wheel, an electro-responsive device, means for stopping said motor, controlled by the electro-responsive device, arranged to operate when the electro-responsive device remains de-energized during the closure of the signaling switch, transmitter connections to connect said signaling switch and electro-responsive device to the main signaling circuit connections, and means controlled by said motor stopping means for connecting said signaling switch and electro-responsive device to the emergency circuit wiring. 75 80 85

15. In a signaling system, the combination with a line having a source of current supply and a signal register, of a plurality of transmitters each comprising a motor, a signal wheel, having number teeth and corresponding stop pins, a signal switch controlled by the number wheel, an electro-responsive controlling magnet having an armature, and a pawl carried by said armature arranged to engage a stop pin when the armature is retracted during a closure 90 95 of the signaling switch.

16. In a fire alarm system, suitable current supply means, a suitable circuit, non-interfering transmitters therein comprising each 100 a motor driven toothed signal wheel, circuit controlling pens operated thereby, an electro-magnet controlled by said pens, and a stop device for the motor, associated with the magnet armature for operation to stop 105 the motor only when the armature is retracted during the period of closure of the circuit controlling pens.

17. In a signaling system, the combination with a suitable signaling circuit and current supply means of a transmitter comprising a motor, a make and break device operated thereby, a main switch comprising upper and lower contacts, the former connected in series and the latter in parallel 110 115 with the make and break device, a reciprocating slide having a contact arm for co-action with either the upper or lower contacts, spring means for moving said slide to lower position, means for lifting said slide to upper position, and a motor releasable latch for holding said slide in upper position.

18. In a signaling system, the combination with a spring motor having a winding 125 arbor, a number wheel, and make-and-break devices, of a main switch for controlling the electrical connections of the transmitter comprising switch contacts, a slide associated with said switch contacts carrying 130

- a switch blade, means for moving said slide to various positions controlled by the winding arbor, latching means for the switch blade to latch it in different positions, controlled by the winding arbor.
5. 19. In a signaling system, connections to establish a normal circuit, connections to establish an emergency circuit, and a transmitter comprising a signaling switch normally included in the main signaling circuit, a number wheel for said switch, a motor for said number wheel, means automatically to disable the motor upon rupture of the main circuit, means to close said emergency circuit connections upon the occurrence of such stoppage of the motor, and means responsive to closure of the emergency circuit throughout for connecting the signaling switch in the emergency circuit and removing the disability of the motor.
10. 20. In a signaling system, normally closed main signaling circuit connections, emergency circuit connections normally open at a central station and at each transmitter, and transmitters each comprising a signaling switch normally connectible with the main signaling circuit, a number wheel for said switch, a driving motor for said number wheel, means automatically to close the emergency circuit connections within the transmitter and to connect the signaling switch in said emergency circuit when the main circuit is broken and the emergency circuit otherwise closed, and means automatically to stop the transmitter motor when no circuit is provided for the signaling switch.
15. 21. In a signaling system, the combination of a main circuit, including central-station apparatus and a plurality of transmitters, each transmitter having a signaling switch normally connectible in the main circuit, normally open emergency circuit connections from the central station to the several transmitters, and current-operated means in each transmitter responsive to the establishment of the emergency circuit and rupture of the main circuit for automatically varying within the transmitter the wiring connections of the signaling switch to connect it in operative relation to the emergency circuit.
20. 22. In a signaling system, the combination of a main circuit including central-station signal-receiving apparatus and a plurality of transmitters, each transmitter having signal transmitting means, and electro-responsive non-interference devices for stopping the transmitter, normally connectible in the main circuit, normally open emergency circuit connections from the central station to the transmitters, and current operated means in each transmitter responsive to rupture of the main circuit and establishment 65 of the emergency circuit to vary the wiring connections within the transmitter for connecting said signaling means and electro-responsive non-interference devices in the emergency circuit.
25. 23. In a signaling system, the combination of main circuit connections, normally open emergency circuit connections, means for closing the latter, and a plurality of non-interfering signal transmitters, each comprising motor driven signaling means normally connectible in the main circuit, automatic motor stopping means for non-interference, an electro-magnet disabling said motor stopping means normally connectible in the main circuit, and current-responsive 75 automatic circuit-changing means controlled by the motor-stopping means and normally connected for inclusion in the emergency circuit connections, for operation, upon rupture of the main circuit and closure of the 80 emergency circuit, to vary the connections of the signaling means and magnet to connect them in the emergency circuit.
30. 24. In a system of the character described, the combination of a suitable circuit and current supply means, of a transmitter providing a make-and-break device for inclusion in said circuit, a motor, a signal wheel driven thereby, a winding part for the motor, a main switch comprising an insulating base, upper and lower contacts thereon, respectively connected in series and parallel with said make-and-break device, a spring-retracted, reciprocatable slide mounted on the side of said base having an arm overlying said base for coöperation with the upper or lower contacts, means to elevate the slide, a latch for said slide, and motor operated latch-releasing means.
35. 25. In a system of the character described, suitable circuits and current supply means therefor, combined with a transmitter providing a make-and-break device, a signal wheel, a motor for said wheel, means for stopping said wheel, a magnet controlling 90 said stopping means when the latter is potentiated for operation, a multiple-position switch and means for mechanically potentiating said motor stopping means for its 95 electrically controlled operation upon movement of said switch to one of its multiple 100 positions.
40. 26. In a system of the character described, suitable circuits, and a motor driven transmitter comprising winding means differently operable for fire alarm and for watch service, automatic non-interference devices, and means responsive to the fire-alarm winding means, and non-responsive to the watch service winding means, for mechanically 105 potentiating the non-interference devices for 110 operation.
45. 27. In a system of the character described, a transmitter having a motor, make-and-break devices operable thereby, winding 115 120
50. 125
55. 130

means, operable to condition the transmitter for distinctive fire alarm and watch service signals, a part movable to different degrees by said different windings, automatic motor-stopping means; for non-interference, comprising a magnet and an armature therefor, and an armature-spring controlled by said movable part, to potentiate said motor-stopping means only when the motor is wound

for fire alarm service; in combination with 10 suitable circuits and current supply means therefor.

In testimony whereof I hereunto set my hand in the presence of two witnesses.

JUDSON McFELL.

In the presence of—

MARY F. ALLEN,

W. LINN ALLEN.
